(57) **CLAIM**

The ornamental design for a manually manipulated therapeutic device, as shown and described.

DESCRIPTION

FIG. 1 is a top, perspective view of a manually manipulated therapeutic device in accordance with the present invention; FIG. 2 is a front view of the manually manipulated therapeutic device, of FIG. 1;

FIG. 3 is a rear view of the manually manipulated therapeutic device of FIG. 1;

FIG. 4 is a right-side view of the manually manipulated therapeutic device of FIG. 1;

FIG. 5 is a left-side view of the manually manipulated therapeutic device of FIG. 1;

FIG. 6 is a top view of the manually manipulated therapeutic device of FIG. 1;

FIG. 7 is a bottom view of the manually manipulated therapeutic device of FIG. 1;

FIG. 8 is a bottom, perspective view of the manually manipulated therapeutic device of FIG. 1;

FIG. 9 is a bottom perspective view of the manually manipulated therapeutic device of FIG. 1 in a folded position;

FIG. 10 is a front view of the manually manipulated therapeutic device of FIG. 1 in a folded position;

FIG. 11 is a rear view of the manually manipulated therapeutic device of FIG. 1 in a folded position;

FIG. 12 is a left-side view of the manually manipulated therapeutic device of FIG. 1 in a folded position;

FIG. 13 is a right-side view of the manually manipulated therapeutic device of FIG. 1 in a folded position;

FIG. 14 is a top view of the manually manipulated therapeutic device of FIG. 1 in a folded position; and,

FIG. 15 is a bottom view of the manually manipulated therapeutic device of FIG. 1 in a folded position.

The broken lines depict portions of the manually manipulated therapeutic device that form no part of the claim.

1 Claim, 14 Drawing Sheets
